(57) **CLAIM**

The ornamental design of a LED emergency light, as shown and described.

DESCRIPTION

FIG. 1 is a perspective view taken from the lower right-hand side of the LED emergency light of the present invention, which has two lamps, each of which can be adjusted around two axes extending perpendicular to each other;

FIG. 2 is a front elevational view of the LED emergency light of FIG. 1;

FIG. 3 is a top plan view of the LED emergency light of FIG. 1;

FIG. 4 is a bottom plan view of the LED emergency light of FIG. 1;

FIG. 5 is an elevational view of the right side of the LED emergency light of FIG. 1; and,

FIG. 6 is an elevational view of the left side of the LED emergency light of FIG. 1.
